CLAIM

The ornamental design for a module for wireless communication device, as shown and described.

DESCRIPTION

FIG. 1 is a top right perspective view of a module for wireless communication device;

FIG. 2 is a bottom plan view thereof;

FIG. 3 is a top plan view thereof;

FIG. 4 is a left side elevation view thereof;

FIG. 5 is a front elevation view thereof;

FIG. 6 is a right side elevation view thereof; and,

FIG. 7 is a rear elevation view thereof.

The broken lines in the drawings depict parts of the module for wireless communications device that form no part of the claim.
